CLAIM

The ornamental design for a French door oven, as shown and described.

DESCRIPTION

FIG. 1 is a perspective view of the French door oven according to my new design;

FIG. 2 is a front view of the French door oven of FIG. 1; FIG. 3 is a cross-sectional view taken at Line 3-3 of FIG. 2; FIG. 4 is a left side view of the French door oven of FIG. 1, the right side view being a mirror image thereof;

FIG. 5 is a cross-sectional view taken at Line 5-5 of FIG. 4; FIG. 6 is a top view of the French door oven of FIG. 1; FIG. 7 is a cross-sectional view taken at Line 7-7 of FIG. 6; FIG. 8 is a bottom view of the French door oven of FIG. 1; and,

FIG. 9 is a rear view of the French door oven of FIG. 1. The broken lines show portions of the French door oven and environment and form no part of the claimed design.

1 Claim, 3 Drawing Sheets
